STRIPING RULER FOR FUR COATS AND THE LIKE

Filed May 2, 1940

FIG. 1.

FIG. 2.

FIG. 3.

UNITED STATES PATENT OFFICE

2,220,753

STRIPING RULER FOR FUR COATS AND
THE LIKE

Fred Chyz, Brooklyn, N. Y.

Application May 2, 1940, Serial No. 332,940

4 Claims. (Cl. 33—107)

This invention relates to new and useful improvements in a striping ruler for fur coats and the like.

More specifically, the invention proposes the construction of a striping ruler constructed in a manner to be utilized for striping or dyeing inferior grades of fur for the purpose of simulating higher grade furs.

Still further it is proposed to characterize the striping ruler by a strip of rigid material having an elevated straight front edge portion along which a tool used for striping is adapted to be moved to facilitate the application of the dyeing material in parallel straight lines.

Still further it is proposed to provide a handle mounted on said strip and extended rearwards thereof and arranged to permit the strip to be conveniently moved along the surface of the fur being striped.

Still further a modification of the invention proposes to construct the strip of rigid material of top and bottom sections arranged for permitting the same to be separated for changing the elevation of the straight edge portion in a manner to control the space between the top surface of the fur and the front edge portion of the strip to prevent the dyeing material from running or being blotted therebeneath.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a striping ruler constructed in accordance with this invention.

Fig. 2 is a plan view of the striping ruler in position upon a piece of fur.

Fig. 3 is an end elevational view of Fig. 2.

Fig. 4 is a plan view of a striping ruler constructed according to a modification of this invention.

Fig. 5 is a vertical sectional view taken substantially on the line 5—5 of Fig. 4.

Fig. 6 is an end elevational view of the striping ruler shown in Fig. 4 but with the sections of the strip thereof in a separated condition.

Fig. 7 is a perspective view, illustrating another form of handle on the striping ruler.

The striping ruler for fur coats and the like, according to this invention, includes a strip of rigid material 10 having an elevated straight front edge portion 10^a on its front side. This strip

of rigid material 10 may be formed from wood, metal, plastic material, or any other similar hard substance which is not easily nicked or marred. The elevated straight front edge thereof is formed by cutting away a portion of the front bottom corner thereof (see Fig. 3) to cause the front edge 10^a thereof to be spaced from the bottom edge of the strip 10.

A handle 11 is securely mounted on the top face of the strip 10 and extends rearwards therefrom provided for permitting the striping ruler to be conveniently moved across the surface of a piece of fur being striped. This handle 11 comprises a section 11^a having its front end securely attached to the top face of the strip and extended rearwards thereof and at right angles thereto. A second section 11^b has its front end securely attached to the top face of the strip 10 and its free end projected rearwards therefrom and obliquely thereto, causing the rear end of the section 11^b to assume a position adjacent the rear end of the section 11^a for permitting these free rear ends to be connected together.

The operation of this form of the invention is as follows:

For striping a piece of fur the striping ruler is securely held in one hand by means of the handle 11 and positioned upon the fur, as shown in Fig. 3, with the handle thereof extending parallel to the fur. The tool being used for striping the fur is moved along the straight front edge 10^a thereof. As each line is striped the ruler is moved rearwards along the face of the fur to expose a new unstriped portion. Due to the fact that the front top edge 10^a is raised above the surface of the fur it is impossible for the fluid being used for striping the fur from running beneath and being blotted between the adjacent faces of the ruler and the fur.

According to the modification of the invention shown in Figs. 4—6 inclusive the construction of the striping ruler is similar to that previously described, except that the strip of rigid material 10 is formed of separate sections 10^b and 10^c and provided with a means for separating the sections for changing the elevation of the straight edge 10^a. It is deemed desirable to change the elevation of the straight edge 10^a of the ruler to compensate for the varying length 45 of the hair or nap of different types of fur. This means comprises a slide 12 mounted within a groove formed in the top section 10^b. This slide 12 is provided with a pair of spaced downwardly extending cams 12^a which engage com- 50

plementary cam recesses 13 formed in the top faces of the section 10^c.

A means is provided for moving the slide 12 relative to the top section 10^b for causing the 5 cams 12^a to move out of the cam recess 13 and engage the top face of the section 10^c for holding the bottom section 10^c spaced from the top section 10^b. This means comprises a pin 14 extending upwards through a slot 15 formed in 10 the top section 10^b. This pin 14 extends upwards through a second slot 16 formed in the section 11^b of the handle 11. The rear ends of the sections 11^a and 11^b of the handle 11 are pivotally connected together by means of a pin 17 and when the section 11^b is moved towards the section 11^a the slide 12 will be moved relative to the top section 10^b to cause the cams 12^a to be disengaged from the cam recesses 13.

A resilient means is provided for urging the 20 section 10^c into face contact with the section 10^b when the slide is in the position illustrated in Fig. 5. This means comprises pins 18 having their bottom ends securely attached to the section 10^c and slidably extended through openings 25 formed in the top section 10^b.

Leaf springs 19 are mounted upon the pins 18 and have their free ends engaging grooves 20 formed in the top face of the section 10^b. The intermediate portions of the leaf springs 19 bear 30 against enlarged heads 21 formed on the upper free ends of the pins 18 for resiliently holding the section 10^c in a raised position with relation to the section 10^b.

In other respects this form of the invention 35 is similar to the previous form and like parts are identified by like reference numerals.

In Fig. 7, the striping ruler 10' is illustrated with a centrally located superimposed block handle for readily tilting the striping ruler to any 40 desired angular position.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I

claim as new, and desire to secure by United States Letters Patent is:

1. A striping ruler for fur coats and the like, comprising a strip of rigid material having an elevated straight edge portion on its front side, and a handle mounted on said strip and extending rearwards, said strip being formed of separate superimposed sections, and means for separating said sections for changing the elevation of said straight edge. 10

2. A striping ruler for fur coats and the like, comprising a strip of rigid material having an elevated straight edge portion on its front side, and a handle mounted on said strip and extending rearwards, said strip being formed of separate superimposed sections, and means for separating said sections for changing the elevation of said straight edge, said means comprising a slide 15 slidably mounted in a groove formed in the bottom face of the upper of said sections, downwardly extending cams formed on said slide and engaging complementary cam recesses formed in the top face of the bottom of said sections, and means controlled by said handle for moving said slide to cause said means to be moved 20 out of said cam recesses to urge said sections apart. 25

3. A striping ruler for fur coats and the like, comprising a strip of rigid material having an elevated straight edge portion on its front side, 30 and a handle mounted on said strip and extending rearwards, said strip being formed of separate superimposed sections, and means for separating said sections for changing the elevation of said straight edge, and resilient means for 35 urging said sections into face contact with each other.

4. A striping ruler for fur coats and the like, comprising a strip of rigid material having an elevated straight edge portion on its front side, 40 and a handle mounted on said strip and extending rearwards, said handle being substantially V-shaped and having the free ends of its arms mounted on the top face of said strip for elevating the rear portion of said handle when the bottom face of said strip is rested on a flat surface to provide a space for one's fingers when gripping said handle. 45
